Truman H. Day.

UNITED STATES PATENT OFFICE.

TRUMAN H. DAY, OF AURORA, ILLINOIS, ASSIGNOR TO HIMSELF AND THE WILCOX MANUFACTURING COMPANY, OF SAME PLACE.

RAIL-SUPPORT FOR DOOR-HANGERS.

SPECIFICATION forming part of Letters Patent No. 394,643, dated December 18, 1888.

Application filed May 15, 1888. Serial No. 273,952. (No model.)

To all whom it may concern:

- Be it known that I, TRUMAN H. DAY, residing at Aurora, in the county of Kane and State of Illinois, and a citizen of the United States, have invented a new and useful Improvement in Rail-Supports for Door-Hangers, of which the following is a specification, reference being had to the accompanying drawings, in which—
- 10 Figure 1 is an end elevation of the support, the rail, and a roller door-hanger. Fig. 2 is a perspective view of the support and rail. Fig. 3 is a front elevation, on a smaller scale, showing a rail and its supports.
- 15 This invention relates to supports for the rails for roller door-hangers. The object is to construct an improved support for the rail, which I accomplish as illustrated in the drawings, and hereinafter described. That which
- 20 I claim as new will be pointed out in the claim.

In the drawings, A represents the side or wall of a building from which the door is supported.

- 25 B is an L-shaped bracket. C is a brace, which can be formed integral with the bracket B, as shown, or it can be made separate from and secured to the bracket B. This brace C consists of a vertical portion, b, an inclined portion, c, a vertical portion, d, to which the rail is riveted, and a horizontal portion, e, which is riveted to the horizontal arm of the bracket B. The

end a of the horizontal arm of the bracket B projects beyond the vertical portion d of the brace C and forms a support for the rail.

D is a flat bar-rail which rests on the projecting end a of the bracket B and is riveted to the vertical portion d of the brace C.

E is a common grooved roller door-hanger, 40 the roller of which runs on the rail D.

The supports may be secured to the wall A by screws which pass through both the vertical arm of the bracket B and the vertical portion b of the brace C, and are placed at such 45 distances apart as may be necessary to properly support the door. When two or more sections of rail D are used, the adjoining ends of two sections rest on a support.

The support, consisting of the bracket B 50 and brace C, is strong, well adapted to hold the rail, and very easily made.

What I claim as new, and desire to secure by Letters Patent, is—

A support for the rail for door-hangers, consisting of an L-shaped bracket, B, and a brace, C, having a vertical portion, d, to which the rails can be secured, and a horizontal portion, e, secured to the horizontal arm of the bracket B a little distance from the outer end 60 thereof, leaving a projecting end, a, to support the rail, substantially as specified.

TRUMAN H. DAY.
